[57] CLAIM

The ornamental design for a chair back, as shown and described.

DESCRIPTION

FIG. 1 is a front view of the chair back;
FIG. 2 is a side view looking in the direction of the
arrow 2 of FIG. 1 of the chair back;
FIG. 3 is a back view looking in the direction of the
arrow 3 in FIG. 2 of the chair back;
FIG. 4 is a top view looking in the direction of the
arrow 4 of FIG. 3 of the chair back;
FIG. 5 is a bottom view looking in the direction of the
arrow 5 of FIG. 3 of the chair back; and
FIG. 6, which appears on sheet 1 of the drawings, is a
longitudinal sectional view taken along the line 6—6 of
FIG. 1.
